UNITED STATES PATENT OFFICE

IRENE FOGEL AND SATCHÉ SHULKIN, OF LOS ANGELES, CALIFORNIA

DESIGN FOR A BATHING SUIT

Application filed April 28, 1931. Serial No. 39,648. Term of patent 3½ years.

To all whom it may concern:

Be it known that we, IRENE FOGEL and SATCHÉ SHULKIN, citizens of the United States, residing at Los Angeles, in the county of Los Angeles and State of California, have invented a new, original, and ornamental Design for a Bathing Suit, of which the following is a specification, reference being had to the accompanying drawings, forming part thereof.

We claim:

The ornamental design for a bathing suit, as shown.

Signed at Los Angeles, in the county of Los Angeles, State of California, this 7th day of April, 1931.

SATCHÉ SHULKIN.
IRENE FOGEL.
